RAIL-RETAINING MEMBER

Application filed November 13, 1930. Serial No. 495,816.

This invention relates to rail retaining members and more particularly to means for retaining rails upon tie plates, though in using the term "tie plate" herein we mean to include any form of plate, tie or foundation, upon which the base of a rail is adapted to rest or to be secured.

The principal object of the invention is to provide a form of tie plate and retaining member, which when used in combination will enable rails to be quickly and readily assembled upon their supporting tie plates and to be removed with equal facility.

Heretofore various types of rail fasteners have been proposed for securing rails to ties or tie plates, and such rail fasteners have commonly been designed in the form of wedges, adapted to be driven against the rail with a solid blow and to be held thereagainst by a forced fit, or by elaborate locking devices, or by tie plates fashioned into intricate forms expensive to manufacture. When retaining members are thus driven home against the rail flange, they are frequently distorted from their normal shape, and their removal is a matter of some difficulty. The retaining member of our invention is preferably not driven solidly against the rail, though it may be found to be desirable to provide frictional contact between the end of the retaining member and the rail flange, but it is adapted to be driven to a fixed point and there locked to the tie plate.

Furthermore, the retaining member of this invention is preferably designed to limit movement of the rails with respect to the tie plates rather than to prevent such movement. The retaining members herein described being spaced from the upper surface of the base flange of the rail, there is less of a tendency for the retaining members to be dislodged from their seats, or for the rail supporting ties to be loosened from the underlying ballast. Furthermore, the retaining members are held in place, by a comparatively simple yet effective expedient.

A further object of the invention is to provide a retaining member of resilient ma-

terial, such as spring steel, and to utilize the resilient property of the member in providing a method of holding the same in position while permitting its ready removal.

Further objects and advantages of the invention will be apparent from the description hereinafter of two examples thereof, the description having reference to the accompanying drawings, of which:

Fig. I is an end view of a rail, tie-plate, and retaining member, the rail shown in cross section, illustrating an example of our invention.

Fig. II is a perspective view of a retaining member by itself; and,

Fig. III is a fragmentary view of a modified form of tie plate.

There is shown in the drawings a section of a rail 1 of standard form having a base flange 2 resting on a tie plate 3.

Adjacent to the outside edges of the base flange 2, the tie plate 3 is provided with upstanding lugs 4, each lug being transversely perforated at 5 so as to accommodate a retaining member 6 adapted to project horizontally above the upper surface 7 of the base flange 2. The inwardly projecting end 8 of the retaining member 6 is tapered to provide an inclined surface 9 parallel to the surface 7 of the base flange 2 and spaced therefrom at a predetermined distance. In the example shown this distance is such that the rail flange will only engage the retaining member 6 upon a considerable vertical movement of the rail 1 with respect to the tie plate 3.

In the example shown, the retaining member 6 comprises a flat spring steel bar, and when manufactured it is bent to the form of a hook with the end 10 curved to assume a normal shape substantially corresponding to the rounded tops 11 of the lugs 4 of tie plates 3. Obviously, a bar of circular cross-section, or of other desired cross-sectional shape, may be used in lieu of the particular shape selected for illustration herein. At 12 the lower curved surface of the outer end of the retaining member 6 changes in contour from a downward curve to an upward curve, thus providing a ridge

assisting the operation of inserting the retaining member within a tie plate lug and resisting dislodgment of the retaining member when it has been inserted.

5 The retaining member 6 may be readily applied to the tie plate 3 by inserting the end 8 within the perforation 5 and then striking the back of the member with a moderate blow causing the member to be thrust 10 inward and at the same time causing the ridge 12 to catch yieldingly on the inside of the rounded top 11 of the lug 4.

To remove the retaining member 6 a moderate force applied to the end 10 in an upward direction coupled with an outward pull 15 is sufficient. Accordingly, the retaining member is made to possess only such resiliency as to enable it to be applied and removed with facility.

20 In Fig. III another form of rail fastener embodying our invention is shown. In this instance the tie plate 3a is provided with upstanding lugs 4a having a number of rounded depressions 13 and 14 in the top thereof.

25 The retaining member 6a is likewise made in the form of a hook with a knob 12a at the end thereof. The lower end 8a is inserted through a perforation 5a in the lug 4a, so as to project above the rail flange 7, and the 30 amount of clearance between the inclined surface 9a and the base 7 of the rail can be varied according to the position assumed by the retaining member. When the retaining member is in the position illustrated in 35 which its knob 12a engages the outermost depression 13, there is a considerable clearance between the inclined surface 9a and the base 7 of the rail. The retaining member may, however, be driven closer to the 40 rail to a position in which its knob 12a engages the innermost depression 14, in which case there is virtually no clearance between it and the rail, or it may be driven to a still closer position in which its knob 12a engages 45 the inner edge 15 of the lug 4a in which case the retaining member is driven solidly against the base of the rail. Accordingly, the form of tie plate shown in Fig. III provides for three positions (and 50 obviously provision may be made for any desired number of positions) into which the retaining member is adapted to be driven, the selection of the desired position depending upon the amount of clearance desired 55 between the end of the retaining member and the base of the flange. The retaining member 6a is likewise made of such material and of such normal shape as to resist distortion to an extent that it is not easily dislodged while sufficiently resilient to enable 60 it to be easily applied and removed with the use of tools.

While we have described two examples of our invention it will, of course, be apparent 65 that various changes may be made in the

form of the tie plates and rail retaining members herein described without departing from the spirit of our invention which contemplates a variety of forms for these parts.

Having thus described our invention, we 70 claim:

1. In combination, a rail, a tie plate having an upstanding lug, and a retaining member in the form of a hook having one end passing through said lug to a position above 75 the rail flange and the other end caught on the surface of said lug.

2. In combination, a rail, a tie plate having an upstanding lug, and a retaining member comprising a resilient hook having one end passing through said lug and the other end caught on the surface of said lug. 80

3. In combination, a rail, a tie plate having an upstanding perforated lug with a rounded top, and a retaining member comprising a resilient hook having one end passing through the perforation in said lug and having the other end curved to conform to the rounded top of said lug. 85

4. In combination, a rail, a tie plate having an upstanding lug with a rounded top, and a spring steel retaining member in the form of a hook having one end passing through said lug and having the other end curved downward to conform to the rounded 95 top of said lug and then curved upward whereby when the retaining member is inserted it is caught on the top of said lug yet readily removable.

5. In combination, a rail, a tie plate having an upstanding lug, and a retaining member of resilient material in the form of a hook having one end passing through said lug to a predetermined position with respect to the flange of said rail and the other end 100 caught around said lug.

6. In combination, a rail, a tie plate having an upstanding lug, and a retaining member of resilient material in the form of a hook having one end passing through said lug, said end being tapered to provide an inclined surface, and having the other end caught around said lug, whereby said inclined surface is spaced at a predetermined 110 position above the flange of said rail. 115

7. In combination, a rail, a tie plate having an upstanding lug and a retaining member in the form of a hook having one end passing through said lug to a position above the rail flange and the other end caught on the surface of said lug, said lug being formed to provide a plurality of positions at which the retaining member is adapted to be caught. 120

8. In combination, a rail, a tie plate having an upstanding lug with a plurality of depressions in the surface thereof, and a retaining member in the form of a hook having one end passing through said lug to a position above the rail flange, and the 125 130

other end provided with a knob adapted to catch in any one of said depressions.

9. A rail retaining member in the form of a hook adapted to catch in a predetermined position on a tie plate lug, said member being of a resilient material, yet offering sufficient resistance to deformation to prevent its dislodgment in service.

10. A rail retaining member in the form of a hook adapted to catch in any one of a plurality of predetermined positions on a tie plate lug, said member being of a resilient material, yet offering sufficient resistance to deformation to prevent its dislodgment 15 in service.

In testimony whereof, we have hereunto set our names at Philadelphia, Pennsylvania, this 10th day of November, 1930.

ROBERT FARIES.
ROBERT H. BOYD.
